UNITED STATES PATENT OFFICE

106,559

DESIGN FOR A DRESS ENSEMBLE

Joan Bayor, New York, N. Y.

Application August 31, 1937, Serial No. 71,393

Term of patent 3½ years

To all whom it may concern:

Be it known that I, Joan Bayor, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear jacket portion is conventional and is studded like the front.

The ball ornaments on the sash are comprised of bead elements.

I claim:

The ornamental design for a dress ensemble, substantially as shown, and described.

JOAN BAYOR.
